CLAIM

The ornamental design for a hand held spot light, substantially as shown.

DESCRIPTION

FIG. 1 is a side elevational view of a hand held spot light showing my new design.

FIG. 2 is a bottom plan view.

FIG. 3 is a side elevational view opposite from that shown in FIG. 1.

FIG. 4 is a front elevational view.

FIG. 5 is a top plan view.

FIG. 6 is a rear elevational view.
